UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A PERCOLATOR-POT.

45,331.

Specification for Design.

Patented Mar. 3, 1914.

Application filed December 11, 1913. Serial No. 806,114. Term of patent 7 years.

To all whom it may concern:

Be it known that I, EDWARD A. FARR, a citizen of the United States, residing at Meriden, New Haven county, Connecticut, have invented a new, original, and ornamental Design for a Percolator-Pot, of which the following is a specification, reference being had to the accompanying drawing, forming a part thereof, in which the figure

is a view in side elevation of the complete pot, illustrating my new design.

I claim:

The ornamental design for a percolator pot, as shown.

EDWARD A. FARR.
